DESIGN FOR A PENHOLDER OR SIMILAR ARTICLE

Harry O. Sandberg, Boston, Mass., assignor to Northeastern Plastics, Inc., Boston, Mass., a corporation of Massachusetts

Application August 8, 1946, Serial No. 132,363

Term of patent 7 years

(Cl. D74—17)

To all whom it may concern:

Be it known that I, Harry O. Sandberg, a citizen of the United States, residing at Boston, in the county of Suffolk and State of Massachusetts, have invented a new, original, and ornamental Design for Penholder or Similar Article, of which the following is a specification, reference being had to the accompanying drawing, forming part thereof.

In the drawings,

Fig. 1 is a front elevation of a penholder or similar article showing my new design; and

Fig. 2 is a side elevation of said penholder.

I claim:

The ornamental design for a penholder or similar article, substantially as shown.

HARRY O. SANDBERG.
